UNITED STATES PATENT OFFICE.

JOHN W. WAY, OF EDGEWORTH, PENNSYLVANIA.

AEROPLANE.

REISSUED

1,014,731.

Specification of Letters Patent.

Patented Jan. 16, 1912.

Application filed November 15, 1909. Serial No. 528,200.

To all whom it may concern:

Be it known that I, JOHN W. WAY, residing at Edgeworth, in the county of Allegheny and State of Pennsylvania, a citizen 5 of the United States, have invented or discovered certain new and useful Improvements in Aeroplanes, of which improvements the following is a specification.

In the specification which forms part of 10 another copending application filed November 15, 1909, Serial No. 528,199, I have shown and described a propeller wheel particularly adapted for service in aeroplanes, in which the blade or vane of the propeller 15 is transversely arched and provided on its concave surface with air-retarding projections. The invention which I am about to disclose and make the subject of this application is the employment of this same configuration to the sustaining wings or sails of an aeroplane.

The accompanying drawings illustrate my invention. In them, Figure 1 is a fragmentary view in perspective of two coöperating wings or sails of an aeroplane; and Fig. 2 is a sectional view of a single section.

Each of these wings or sails is composed of a number of sections or parts 2, which are arranged in succession from front to 20 rear, meeting at their edges, and forming the wings or sails. The direction of progress is indicated by the arrow α . Each one of the several sections of these sustaining wings or sails is formed with such a contour as I 25 have, in my other application referred to above, described for the blades of a propeller; that is to say, each of these sections is transversely curved, the convex side being the upper side, and the concave side, the 30 lower side; the form of curve is preferably spiral, and the arrangement such that the spiral increases in radius from the anterior to the posterior edge of each section. Furthermore, the forward edge of the lead- 35 ing section is rounded; at the point of meeting of adjacent sections there is a protruding rounded edge; and in the concave face of each section and adjacent to the anterior edge thereof are arranged one or more air- 40 retarding projections extending longitudinally of the section and protruding preferably in a rearward direction. These projections are preferably flexible, and are preferably vented for the passage of restricted 45 quantities of air. If there be but one such

projection in a section, it will preferably be arranged at the very edge, immediately rearward of the rounded portion 3 or 7; and, if there be more projections than one, they are preferably formed of increasing length from 60 the foremost to the rearmost of the series within a single section.

The forward rounded edge of the leading section is indicated at 3 in the drawing, the 65 projections at 4, and the protruding rounded edge at the point of meeting of adjacent sections at 7. The vents through the projection 4 are preferably in the form of perforations 5.

The entire wing or sail may if preferred 70 consist of a single section such as I have described above. Such simple wing structure is illustrated in section in Fig. 2 of the drawings. In this case, while the major portion of the wing is rigid the posterior edge (and, 75 in case a plurality of sections are employed, the posterior edge of the rearmost section) will preferably be made flexible.

My invention further resides in a certain 80 collocation or relative arrangement of two coöperating wings or sails such as I have described and such as the drawing illustrates. It will be understood that as an 85 aeroplane provided with wings of this particular shape advances in the direction indicated by the arrow α , condensation and rarefaction of the air adjacent to the wing surfaces will occur; and it is my object to so 90 arrange the two coöperating wings with respect to one another that such condensation and rarefaction will effect the least possible amount of resistance in the air to the 95 progress of the vessel. It is manifest that, on the under surface of the wings, condensation will be greatest at or near the forward 100 or anterior part of each section, where the protuberances are located, while a corresponding tendency to rarefaction will occur toward the posterior edge of each section. Similarly, upon the upper surfaces of each 105 wing, condensation will be greatest near the anterior edge of each section, and least at the posterior edge. Such being the general condition of things so far as concerns air pressure, I have found the best relative arrangement to consist in having the succeeding sections of the underlying or lower sail arranged slightly rearward of the corresponding sections of the upper wing or sail, to the end that the spaces of greatest con- 110

densation of air between the two blades shall not lie directly opposite one another, but shall be arranged in alternation, adjacent first to one wall and then adjacent to the 5 other wall of the confined space. In such arrangement I have found there is the least resistance to the progress of the vessel. In the drawing I have indicated in dotted lines in an approximate manner the spaces of 10 condensation of air between the adjacent wings or sails, in this way illustrating more clearly the relative arrangement of these parts. It will of course be understood that I have found in this particular configuration of the wings or sails, a positive advantage over plain surfaces.

I claim herein as my invention:

1. A sustaining wing for an aeroplane, said wing being of curved contour and having the continuity of its concave surface interrupted at a point rearwardly of but adjacent to its anterior edge by a projection which extends outwardly from the said concave surface, said projection forming with 25 the concave surface a constantly open pocket.

2. A sustaining wing or sail for an aeroplane of curved contour from front to rear, and provided upon its concave surface and adjacent to the anterior edge thereof with a 30 vented air-retarding projection, substantially as described.

3. A sustaining wing or sail for an aeroplane of curved contour from front to rear, and provided upon its concave surface with 35 a series of air-retarding projections, the length of the projections of the series increasing from the foremost rearwardly, substantially as described.

4. A sustaining wing or sail for an aeroplane composed of a plurality of segments arranged edge to edge and united along their adjoining edges, each of said segments being of curved contour in cross section, the

posterior edge of the rearmost section being flexible, substantially as described. 45

5. In an aeroplane, the combination of two arched supporting wings or sails arranged one above another and one in advance of the other in such relative positions that the condensation of air adjacent to the 50 under surface of the upper wing due to the motion of the vessel shall be opposed to the rarefaction of air adjacent to the upper surface of the lower wing, substantially as described. 55

6. In an aeroplane, the combination of two supporting wings or sails arranged one above the other, each of said wings or sails consisting of a plurality of arched segments and the said sails or wings being so arranged with respect to one another that those portions of the under surface of the upper wing where condensation is greatest shall lie opposite to the portions of the upper surface of the lower sail where the pressure is the least, and the portions of the under surfaces of the upper sail where the density of the air is least shall stand opposed to the portions of the upper surface of the lower wing where condensation is 60 greatest, substantially as described. 65

7. A sustaining wing or sail for an aeroplane, composed of a plurality of segments each of curved contour in cross section, convex above and concave below, said segments 75 united edge to edge and arranged with their united edges transverse to the line of motion of said wing or sail, substantially as described.

In testimony whereof I have hereunto set 80 my hand.

JOHN W. WAY.
